UNITED STATES PATENT OFFICE.

GEORGE LLOYD, OF BROOKLYN, ASSIGNOR TO MAXMILLIAN CALM, OF NEW YORK, N. Y.

DESIGN FOR A BOTTLE.

SPECIFICATION forming part of Design No. 23,174, dated April 10, 1894.

Application filed February 21, 1894. Serial No. 501,051. Term of patent 14 years.

To all whom it may concern:

Be it known that I, GEORGE LLOYD, a subject of the Queen of Great Britain, and a resident of Brooklyn, in the county of Kings and State of New York, have invented a new and original Design for Bottles, of which the following is a specification.

Figure 1 is a side elevation showing one side of a bottle embodying my invention. Fig. 2 is a side elevation showing the other side of the bottle; and Fig. 3 is a bottom view of the bottle.

The leading feature of my design consists in a convexly curved surface forming one side of the body of the bottle, and two surfaces arranged so as to substantially form a wedge on the opposite side of the body of the bottle.

A is the convexly curved surface forming one side of the body of the bottle, and B and C are the two surfaces meeting in the line D

so as to form a wedge on the opposite side of the body of the bottle. The neck E is joined to the body of the bottle by sloping shoulders F and G. The surfaces A, B and C are counter sunk so as to form panels, the surface A being surrounded by the raised rim a, the surface b being surrounded by the raised rim B, and the surface C being surrounded by the raised rim c.

What I claim, and desire to secure by Letters Patent, is—

The design for a bottle consisting of the design, substantially as shown and described.

In testimony whereof I have signed my name to this specification in the presence of two subscribing witnesses.

GEORGE LLOYD.
